UNITED STATES PATENT OFFICE.

VAN VECHTON RIESBERG, OF PHILADELPHIA, PENNSYLVANIA, ASSIGNOR OF ONE-HALF TO FRANK H. DOUGHERTY, OF PHILADELPHIA, PENNSYLVANIA.

RADIATOR-VALVE.

1,291,148.

Specification of Letters Patent. Patented Jan. 14, 1919.

Application filed November 28, 1917. Serial No. 204,319.

To all whom it may concern:

Be it known that I, VAN VECHTON RIESBERG, a citizen of the United States, and a resident of the city of Philadelphia, county 5 of Philadelphia, and State of Pennsylvania, have invented certain new and useful Improvements in Radiator-Valves, of which the following is a specification.

This invention relates to a valve mechanism for radiators which permits the air or other vapor to escape from the radiator and also operates to prevent the ingress of air thereto. It is well known that when the heating fluid, such as steam or water vapor 15 or the like, is turned off from a radiator the residual steam condenses tending to form a partial vacuum in the radiator, and if the automatic valve is then open then atmospheric air is forced into the radiator in view 20 of the vacuum created. This results in tending to fill the radiator with atmospheric air which must be displaced when the radiator is again turned on, thus interfering with the circulation of the heating fluid as well as 25 delaying the time with which the radiator will be heated up. It is the object of this invention to overcome these difficulties and provide a simplified form of mechanism therefor which may be readily manufactured 30 and which operates automatically to prevent to a large degree any ingress of air to the radiator when the heating fluid is turned off and a partial vacuum is formed therein. In this manner the vacuum is partially maintained 35 in the several radiators of a heating system so that the circulation is greatly facilitated. In fact, I have found that it is possible to operate a heating system under pressure of less than one pound and eliminate 40 the necessity for the use of circulating pumps by the use of my valve mechanism in contradistinction to the usual steam pressure in some systems of from fifteen to twenty pounds and in which circulating pumps or 45 vacuum pumps are also necessary.

It is also the object of my invention to use the valve mechanism for the purposes just stated, namely, to prevent the ingress of air to a radiator in combination with a novel 50 operating valve mechanism which will permit any air or vapor which may possibly remain in the radiator to be driven therefrom when the steam or heating fluid is turned on, including a novel thermostatic valve of 55 simple construction which operates to pre-

vent the escape of steam after any residual air has been driven out as aforesaid.

Further objects of my invention relate to the mechanical construction of the valve mechanism used which may be of simple construction and economical to manufacture, comprising a minimum number of parts which are not liable to get out of order but operate in an efficient manner for the purposes intended.

Referring to the drawings, wherein is illustrated one embodiment for carrying my invention into practice, Figure 1 represents a sectional view with the valve mechanisms in the position which they assume when the radiator is turned off and in an unheated condition. Fig. 2 is a similar view showing the position of the valve mechanisms when the steam has just been turned on and before the thermostat has been heated, while Fig. 3 represents a similar view with the heating fluid turned on in the radiator and the thermostat expanded to prevent the escape of the fluid therefrom.

It is, of course, understood that various 80 detailed forms of constructions might be readily utilized to carry my invention into effect and the form illustrated herewith is only shown by way of exemplification of one form, and, as shown, 1 represents a suitable 85 hollow base provided with the cavity 2 and a nipple 3 adapted to be attached to the radiator by way of the screw threads 4, for example. Secured to the base 1 is a casing 5 provided with a transverse partition 6 at 90 its upper end, the partition 6 being provided with an orifice 7 which in the form illustrated may form the orifice through which any air or vapor may escape from the radiator, the same being automatically controlled 95 to prevent the escape of the heating fluid and also prevent the ingress of air, as indicated above. It is to be understood that the base 1 and casing 5 may be of one piece as well as of two parts as just described and 100 the two form a casing or chamber within which may be located any form of thermostatic device, such as the tube 10, adapted to contain a liquid, such as mercury, which, when expanding, operates on a suitable valve 105 11 to close the opening 7.

An efficient arrangement for fixing the tube 10 in position within the casing 5 is illustrated in the drawings by way of the inverted cup-shaped member 12 provided 110

with a central opening through which the tube 10 extends, the same being secured to the cup 12, for example, by reason of the outer flange 13 and a bead or projection 14 on opposite sides of the transverse wall 15 of the cup 12. The transverse wall 15 of the cup or sleeve 12 is provided with openings the sum of the areas of which should preferably be made at least as great as that of the opening 7 for a purpose that will hereinafter appear. The sleeve 12 is adapted to frictionally engage the wall of the chamber 5 and thus rigidly secure the tube 10 in proper operative position in the device.

The opening 7 is adapted to be controlled by a second valve 20 which closes the opening 7 from the outside of the casing 5 and this valve forms one means whereby air 20 is prevented from entering the casing and radiator and at the same time air from the radiator is permitted to escape therefrom. Various forms of valve constructions could readily be used for this purpose and the 25 valve 20 could be maintained in proper operative position by different arrangements or devices but one form therefor constitutes a cap 22 adapted to be frictionally held over the partition 6 in the casing 5 and spaced therefrom forming a second partition or 30 wall above the partition 6 and of course both the partition and wall could be located entirely within the casing. The cap 22 is provided with a plurality of openings 23 and it is my intention to make the size of 35 the openings 23 such as that the sum of the areas thereof is not less than the area of the opening 7 in the same manner that the openings in the wall 15 of the sleeve 12 are 40 not substantially less than the area of the opening 7, with the result that a continuous opening from the interior of the casing 5 to the exterior atmosphere is substantially unrestricted or the same area throughout. 45 The valve 20 is provided with a rib 25 which is adapted to prevent the valve 20 from closing the openings 23, as is clearly shown in Fig. 2, and therefore the partitions 6 adjacent the opening 7 may likewise be provided with a ridge or rib 7' adapted to form 50 a seat for the groove formed on the under-side of the rib 25 of the valve 20. It will be further noted that the space between the valves 11 and 20 and the walls of the casing 55 or cap, respectively, may also be such as to permit the free escape of any air or vapor from the radiator, as will hereinafter appear, and further, that this area of open space I prefer should not be less than the 60 area of the opening 7.

The operation of my invention will be readily understood from the foregoing description and the accompanying drawings where it will be seen that with the parts 65 in the position shown in Fig. 1 and the

steam or other heating fluid is turned on to the radiator, the steam will operate to force any residual air or other vapor within the radiator out through the nipple 3 and chamber 5 through the openings in the cup 15, 70 around the edge of the valve 11 and through the opening 7, forcing the valve 20 into the position shown in Fig. 2, the air in the meantime passing around the edge of the valve 20 and out through the orifices 23 in 75 the cap 22. As the steam or heating fluid drives all the air out of the radiator and comes in contact with the tube 10 in the casing 5, it expands the mercury therein which in turn raises the valve 11 to close 80 the opening 7 and thus prevent the escape of steam from the radiator. As no more air is passing out, the valve 20 drops down onto the rib 7' of the partition 6, as shown in Fig. 3, this being the position which the 85 mechanism assumes when the radiator is being maintained in a heated condition.

When the steam is turned off and the radiator cools, thus condensing any steam remaining therein and forming a partial 90 vacuum, the thermostat contracts, thus permitting the valve 11 to move to the position shown in Fig. 1, but the valve 20, which in this position closes the orifice 7, prevents any air from passing into the casing and 95 to the radiator as will be readily apparent. This results in the maintaining within the radiator of at least a partial vacuum which has the advantages hereinbefore set forth of facilitating the circulation of the steam 100 when the radiator is again turned on, thus tending to increase the efficiency of the heating system, permitting its operation under a materially reduced pressure, thus saving coal in operating the plant and also obviating the necessity for the use of circulating pumps as is common in heating systems of any material size.

The detailed construction illustrated in the drawings as one embodiment of my invention is regarded by me as having certain advantages as above suggested in view of the simplicity of its construction and its positive operation. Attention is called to the fact that the valve 11 of the extension or 110 piston thereon which is actuated by the mercury in the tube 10, may be arranged to rest on the upper open end of the tube 10 when in its lowermost position, the tube 6 acting as means for supporting the valve in its inactive position eliminating the necessity of the use of bearings or other arrangements for properly locating the valve 11. The sleeve 12 of the cup-shaped member for retaining the tube 10 in position is also a very 115 simple and efficient arrangement for securing the tube 10 centrally of the casing 5. It is understood, however, that the detailed construction may be widely varied without departing from the spirit and scope of my 125 130

invention as pointed out in the appended claims.

Having thus described my invention, I claim and desire to protect by Letters Patent of the United States:

1. In a device of the character described, the combination of a hollow casing adapted to be secured to a radiator, an inverted cup-shaped sleeve frictionally secured within 10 said casing provided with openings therethrough, a tube suspended from said sleeve and adapted to contain a fluid to operate as a thermostat, a partition across said casing provided with an opening, a valve controlled 15 by said thermostat and adapted to close said opening to prevent egress of a heating fluid and a valve above said partition and adapted to close said opening to prevent the ingress of air to the casing through said opening.

2. In a device of the character described, the combination of a hollow casing adapted to be secured to a radiator, a tube adapted to contain a fluid to operate as a thermostat, a 25 sleeve secured to the upper end of said tube and engaging the walls of the casing to fixedly position the tube in said casing, an opening through said sleeve adjacent said tube, a partition across said casing and provided with an opening, a valve controlled by 30 said thermostat and adapted to close said opening from within said casing, a cap provided with openings therein located on said casing and a valve between said cap and partition to close the opening in the partition from without said casing.

3. In a valve mechanism for radiators, the combination of a casing adapted to be secured to and communicating with a radiator, said casing being provided with an 40 opening to the atmosphere, a valve for controlling said opening, a thermostat for controlling said valve and means to secure said thermostat to said casing comprising a cup-shaped sleeve secured to said tube and cas-

ing, said cup-shaped sleeve being provided with openings connecting said casing with said first-mentioned opening.

4. In a device of the character described, the combination of a hollow casing adapted 50 to be secured to a radiator, a sleeve positioned adjacent the upper end of said casing, a tube located within the casing and adapted to contain a fluid to operate as a thermostat, means extending inwardly from said sleeve 55 to retain the tube in operative position, a partition across the casing provided with an opening, a valve controlled by said thermostat adapted to close the opening from below said partition and a valve located above said partition and adapted to close the opening therein to prevent the ingress of air to said casing.

5. In an attachment for radiators, the combination of a casing provided with a 60 partition having an air exit opening, a ridge around said opening constituting a valve seat, a wall above said partition having a passage therethrough, a valve provided with an annular rib adapted to coöperate with the 65 ridge around the opening in said partition to close the opening and adapted to coöperate with the lower surface of said wall to prevent said valve from closing the passage in 70 said wall.

6. In a valve mechanism for radiators, the combination of a casing adapted to be secured to and communicate with said radiator, said casing provided with a passage to the atmosphere, a valve for controlling said 75 passage, a thermostat for controlling said valve, and means to position said thermostat in said casing by suspending the same from a sleeve engaging said thermostat and the walls of said casing.

In witness whereof, I have hereunto set my hand this 27th day of November, A. D. 1917.

VAN VECHTON RIESBERG.
